TRACTION UNIT FOR A WINDROWER OR THE LIKE

James M. Conner, Glendale, Calif., Donald E. Burrough, Raymond H. Fairbank, and Gust Soteropoulos, Ottumwa, Iowa, and Henry Dreyfuss, South Pasadena, Calif., assignors to Deere & Company, Moline, Ill., a corporation of Delaware

Filed Jan. 9, 1967, Ser. No. 5,360

Term of patent 14 years

(Cl. D40—1)

FIG. 1

FIG. 2

FIG. 3

FIG. 4

FIG. 5

FIG. 6

FIG. 1 is a left front perspective view of a traction unit for a windrower or the like, embodying our new design. The windrower header is shown in dotted lines for purposes of illustration only.

FIG. 2 is a right rear perspective thereof.

FIG. 3 is a left side elevation view of the traction unit only.

FIG. 4 is a plan view thereof.

FIG. 5 is a front elevation view thereof.

FIG. 6 is a rear elevation view thereof.

The dominant features of our design reside in the portions of the drawings shown in full lines.

We claim:

The ornamental design for a traction unit for a windrower or the like, substantially as shown and described.
